JENS P. NIELSEN AND JOSEPH R. RICHER, OF CHICAGO, ILLINOIS; SAID RICHER
ASSIGNOR TO SAID NIELSEN

METHOD OF AND MEANS FOR APPLYING WIRE TO PACKAGES

Application filed September 24, 1928. Serial No. 307,938.

In preparing some classes of sheet material for shipment or storage it is customary to form the material into rolls and to provide disks at each end of the rolls to protect 5 the ends thereof or to secure packages of nails or the like within the rolls. The disks are generally secured in place by a wire or rod which extends through the roll and is attached to the two disks. Generally 10 the wires are supplied with a disk attached to one end of each wire and after threading the free end of a wire through a roll, another disk is slipped over and attached to the free end of the wire by suitably deforming 15 the wire on the outer side of the disk. To hold the disks tightly against the ends of the rolls the wire is stretched longitudinally of the roll and the ends suitably deformed while the wire is thus stretched so 20 that the contraction of the wire will serve to pull the disks against the ends of the roll. One important object of the present invention is to provide a novel tool operable by a series of definitely determined and 25 easily performed movements of a single operating handle to perform both rapidly and efficiently the stretching and deforming operations upon such a wire or rod. For the sake of economy, it is desirable to 30 use a wire of minimum size and it is therefore desirable to stretch and deform the wire without the application of unnecessary stress to the wire and without excessive stretching of the wire. Another object of 35 the invention is to provide for the attachment of end disks to a roll of sheet material whereby wires of a minimum size may be employed without an excessive percentage of breakage, the operation being such that 40 it may be performed quickly and easily. Another object of the invention therefore is to provide a tool for this purpose which is operable to grip and to stretch a wire to a predetermined tension and thereafter to 45 permit the wire to slip through the gripping means in case there is any further movement thereof so that a wire of minimum diameter may be operated upon by unskilled or careless workmen without undue danger of 50 breaking the wire.

Another object of the invention is to provide a tool operable to perform these operations while the disks and wire are in substantially their final position so that when the operations are completed the disks will 55 be rigidly held against the ends of the roll.

A further object is to provide a hand tool for these operations of such a size and shape that it may be easily handled and still have sufficient strength to perform its work. 60

It is a further object of this tool to perform the operations in such a manner that the finished end of the wire will project but a small distance beyond the surface of the disk thereby preventing it being battered or 65 twisted in later handling of the roll and the consequent loosening of the disks.

Other objects and advantages will become apparent from the following description taken in connection with the accompanying 70 drawings, in which:

Figure 1 shows a fragmental side elevational view of a tool embodying the preferred form of the invention.

Fig. 2 is a fragmental end elevational view of the tool as viewed from the left in Fig. 1.

Fig. 3 is a sectional view of a portion of the tool taken along the line 3-3 in Fig. 2 looking in the direction of the arrows.

Fig. 4 is a fragmental sectional view taken along the line 4-4 of Fig. 2.

Fig. 5 shows a tool positioned adjacent the end of a roll of sheet material and operating upon a rod projecting through the 85 roll. The tool is shown partly in section taken along the line 5-5 of Fig. 4.

Fig. 6 is a fragmental sectional view of the tool taken along the line 6-6 of Fig. 1.

While the invention is as a whole susceptible of various modifications and the tool is capable of embodiment in many alternative constructions, we have shown in the drawings and will herein describe in detail the preferred embodiment of the tool 95 and will describe the method according to the preferred practice thereof, but it is to be understood that we do not thereby intend to limit the invention to the specific form of tool and the exact method disclosed but 100

intend to cover all modifications and alternative constructions falling within the spirit and scope of the invention as expressed in the appended claims.

In practicing the method a hand tool may be employed which in the form chosen for disclosure embodies a hollow body designated generally as 10 which forms a housing for a part of the elements of the tool and provides a supporting handle 11 for carrying and handling the tool. This body is preferably formed in two complementary sections as shown in Figs. 2 and 4, which sections are secured together by a plurality of socket-headed bolts 12 engaging the two sections.

At one end of the supporting handle 11 the body 10 is shaped to provide a tubular housing 13 having open ends and disposed at right angles to the handle. One end 14 of the tubular housing is closed by a head 15 positioned in abutment with said end and forming a continuation of said body. To secure the head 15 in position a tubular hub 16 (Fig. 4.) is formed thereon which projects into the end of the tubular housing 13 and is non-rotatably secured therein by engagement of two of the bolts 12 with a pair of notches 17 formed in the hub 16.

The invention contemplates that the particular form of tool shown herein will be positioned for use in the relation shown in Fig. 5 with the rear side 18 of the head 15 adjacent a disk 19 and a washer 20 which are at one end of a roll 21 of sheet material. In this position a wire or rod 22 having one end attached to a similar disk at the other end of the roll 21 (not shown) may extend through the disk 19 and the washer 20 and into a transverse groove 23 (Figs. 1, 2, 4 and 5) formed in the head 15.

The invention also contemplates a mechanism which will operate on the wire 22 immediately adjacent to the washer 20 so as to avoid unnecessary stretching of the wire and to this end mechanism is provided to stretch the wire, and to hold the washer 20 in abutment with the disk and to upset the wire 22 immediately adjacent to the washer so that the tension placed on the wire by the stretching operation will serve to clamp the end disks to the roll.

As shown in Fig. 5, the tool is arranged for use on a dish-shaped end disk and reaches into the disk to deform the rod. In the preferred form shown, the wire 22 is deformed by swaging and means is provided for shearing off the wire, the swaging means and shearing means preferably being mounted on the side 18 of the head 15 which is to be adjacent the disk when the tool is used to operate upon a wire. The swaging means as illustrated herein comprises a stationary member or jaw 25 (Figs. 2, 3 and 5) removably positioned on the side 18 of the head adjacent to and below

the groove 23. A movable swaging member or jaw 26 is mounted parallel to the side 18 of the head on the opposite side of the groove 23 by means of a removable guiding member 27 (Fig. 3) which is secured on the head 15 by means of bolts 28. This swaging member is movable in the guide 27 toward and from the stationary member and is operable to compress or upset the wire 22 adjacent the washer 20 so as to form a pair of lateral projections thereon to engage the washer and hold it in place.

The shearing means in its preferred form comprises a movable shear blade 29 (Figs. 3 and 5) mounted on the head on the same side of the groove 23 as the stationary swaging member 25 and intermediate said swaging member and the side 18 of the head 15. The guiding member 27 preferably extends around the end of the groove 23 and provides guiding means for the movable shearing blade 29. The other shearing blade is provided by the movable swaging member 26 which is recessed at its inner side to provide an edge 30 which cooperates with the movable shearing blade.

For the purpose of reciprocating the movable swaging member 26 and the movable shear blade 29, a pair of stub shafts 32 and 33 (Figs. 3 and 4) are mounted in the head 15 on opposite sides of and perpendicular to the jaws so as to extend out of the head beyond the side 18 upon which the movable shearing and swaging members are mounted, and on these projecting ends radially projecting fingers 35 are rigidly mounted. The fingers 35 are arranged to project into circular side openings 34 formed in the movable members 26 and 29 so that a rocking movement of the shaft 32 will serve to reciprocate the movable swaging member 26 while a rocking motion of the shaft 33 will serve to reciprocate the shearing member 29.

In the present instance the means for rocking the two shafts 32 and 33 comprises an arm 36 (Figs. 1, 2 and 5) secured on the squared end of the shaft 32 and projecting along the tubular housing toward the supporting handle 11 and a second arm 37 secured to the squared end of the shaft 33 and projecting therefrom substantially parallel to the first arm 36. The ends of these two arms 36 and 37 are disposed on opposite sides of a cam shaft 38 (Figs. 1, 4 and 6) which projects through the handle 11 adjacent the tubular housing 10. A pair of cam disks 39 and 40 are supported on the end of the cam shaft 38 by means of a nut 41 and are arranged to engage suitable cam rollers 42 and 43 secured on the ends of the two arms 36 and 37 respectively. A contractile coil spring 44 is provided with its opposite ends secured to the arms 36 and 37 by means of screws 45 so as to urge the two cam rollers against the cam disks, thus tend-

ing to separate the swaging members and the shearing members.

The outer cam disk 39 is engaged by the cam roller 42 of the arm 36 which operates the swaging member 26 and the surface of this cam disk is arranged so that during clockwise rotation of the cam shaft 38 (Fig. 1) the cam roller 42 will be pressed outwardly during the first part of the rotation of said shaft to operate the jaw 26 to upset the wire adjacent the washer 20. The other or inner cam disk 40 is of a similar form but is arranged to press its cam roller 43 outwardly after the completion of the upsetting or swaging operation to operate the jaw 29 to sever the wire outwardly of the upset portion. Thus the swaging of the wire 22 will be completed before the wire is sheared off.

For the purpose of rotating the cam shaft 38 a hollow shaft 47 (Figs. 1, 4 and 6) is mounted within the tubular housing 13 in coaxial relation to the hub 16 and is secured therein by engagement of two of the bolts 12 with an annular groove 48 formed in the hollow shaft. Within the tubular housing 13 a worm 49 is formed on the outer surface of the hollow shaft 47 which engages a pinion 50 fixed on the cam shaft 38 within the housing formed by the hollow supporting handle 11. Thus by rotation of the hollow shaft 47 the cam shaft 38 may be rotated and the swaging and shearing means operated.

The tool is also provided with means for gripping and stretching the wire prior to the performance of the swaging and shearing operations. In the present instance this means comprises a rod 52 slidably mounted within the tubular hub 16 and the hollow shaft 47 and having gripping means on the end adjacent the swaging and shearing means. In its preferred form this gripping means is arranged so as to be automatically operable to grip the wire during the movement of the rod away from the swaging and shearing means and to release the wire upon the return movement of the rod. Thus in the present instance one end of the rod 52 (Fig. 4) is shaped so as to form one jaw 53 of a gripping device and a hook shaped jaw 54 is pivotally mounted on the rod for cooperation with the jaw 53. At the rear end of the pivoted jaw 54 a finger 55 projects upwardly and is arranged to travel in a longitudinal groove 55^a formed in the tubular hub in the head 15. This finger serves to hold the rod 52 against rotation and also serves during movement of the rod 52

toward the swaging and shearing means to engage an abutment formed by a pin 56 positioned in the groove to automatically open the gripping jaws. A cam surface 57 is formed on the outer side of the hook shaped jaw 54 which engages the pin 56

during the first part of the movement of the rod away from the swaging and shearing means so as to automatically close the gripping jaws.

Since the stretching of the wire 22 is accomplished by the rod 52 which moves along the path perpendicular to the portion of the wire which is to be stretched, an anti-friction roller 58 is positioned in the groove 23 so as to avoid breaking of the wire.

The invention contemplates the provision of a hand tool adapted for rapid and efficient operation and in order to guard against excessive tensioning of the wire 22, the tool is preferably constructed so that after the wire has been brought to a predetermined tension it will be permitted to slip through the gripping jaws during the remainder of their movement. For this reason the hook shaped jaw 54 is used and a slot 54^a is provided in the side of the head 15 so that the wire 22 will be given only one right angle bend during the stretching operation.

In the preferred form of the invention, a single operating handle is provided for moving the rod 52 back and forth to grip and stretch the wire, and for rotating the hollow shaft 47 to accomplish the swaging and shearing operations. In the present instance this means is mounted in a pair of lugs 60 projecting laterally from opposite sides of a longitudinal slot 61 formed at the outer end of the hollow shaft 47. A gear segment 62 is pivotally secured between the two lugs 60 and is arranged to engage a rack 63 formed by annular teeth on the adjacent end of the rod 52. A tubular handle 64 is secured on the gear segment and a hand piece 65 is mounted on the outer end of the tubular handle 64 to facilitate the use of the handle 64 for rotation of the hollow shaft 47. The provision of the annular rack 63 makes possible the rotation of the hollow shaft 47 about the rod 52 by means of the crank handle 64 after the completion of the stretching operation.

The invention contemplates that the stretching operation of the wire by movement of the rod 52 will require considerable force and in order that this operation may be easily performed the cam disks 39 and 40 are so positioned on the cam shaft that when the shearing and swaging jaws are open the handles 11 and 64 will lie substantially in the same plane. Thus the stretching operation may be performed on the wire by pressing the ends of the two handles toward each other as in the case of a pair of shear handles. After the wire has been gripped and stretched by movement of the crank handle 64 toward the handle 11 the swaging and shearing operations may be quickly and easily performed by rotation of the hollow shaft by the crank handle 64.

It will be noted that the movement of the

handle 64 from a position substantially parallel to the rod 52 (as shown in Fig. 1) to a position substantially perpendicular thereto (as shown in Fig. 4) will provide a definite amount of stretching movement which, together with shape of jaws to allow wire to slip upon reaching predetermined tension permits of rapid and efficient operation and will obviate possibility of a workman stretching the wire to too great an extent.

From the foregoing it will be apparent that the invention provides a novel and advantageous method of attaching the end disks to a roll of sheet material by which method the disks may be more quickly and easily attached than heretofore without undue breaking of the wires.

It will also be seen that the invention provides a novel and convenient hand tool for operating upon wires or the like which is quickly and easily operable by a series of definitely determined movements of a single crank handle to stretch a wire, to deform the wire adjacent a package and to cut off the wire after the deforming operation.

It will also be apparent that since the tool provides for stretching the wire to a definite tension and for deforming the wire without unnecessary stretching thereof, the tool will serve to accomplish the result desired without unnecessary breaking of the wires or rods used. Hence there will be considerable saving of time and material resulting from the use of the tool provided.

We claim as our invention:

1. In a tool of the character described, the combination of a body, means mounted on said body operable to deform a wire, means mounted on said body including a rotatable member for operating said deforming means, and gripping and stretching means comprising a rod mounted in said body for longitudinal sliding movement, a handle mounted on said rotatable member operable to move said rod longitudinally and to rotate said member, and means on the one end of said rod automatically operable during sliding movement of said rod to grip or release a wire, said gripping means comprising a jaw rigid with said rod, a movable jaw pivoted on and arranged to cooperate with said rigid jaw to grip a wire, a groove in said body parallel to said rod, an abutment in said groove, a finger on said movable jaw arranged to move in said groove to prevent rotation of said rod in said body and to strike said abutment to open said jaw when moved in one direction, said abutment closing said jaw by striking it as the rod is moved in a reverse direction.

2. In a tool of the character described, the combination of means for deforming a wire or the like, means including a rotat-

able member for operating said deforming means, and gripping and stretching means comprising a rod slidable longitudinally in said rotatable member, means on one end of said rod to grip the wire, means operable to move said gripping means into a gripping position during the first part of the longitudinal movement of said rod in one direction and to continue to hold said gripping means in said gripping position during the remainder of said movement whereby to cause a stretching of a wire by the further movement of said rod, and an operating handle mounted on said rotatable member for moving said rod longitudinally and for rotating said member.

3. In a hand tool of the character described, the combination of means for swaging a wire, means for stretching a wire, and operating means for said two means including a handle having two operating movements one of which operates said stretching means and the other of which operates said swaging means.

4. A hand tool of the character described comprising, in combination, a body, means for stretching a wire, means for deforming such a wire, and actuating mechanism for said means including a single operating handle arranged so that one of said means will be operated when said handle is moved in a given direction and the other of said means will be operated when said handle is moved in a direction transverse to said given direction.

5. A hand tool of the character described comprising, in combination, a body, means for stretching a wire, means for severing such a wire, and actuating mechanism for said means including a single operating handle arranged so that one of said means will be operated when said handle is moved in a given direction and the other of said means will be operated when said handle is moved in a direction transverse to said given direction.

6. In a tool of the character described, the combination of a body, means on said body operable to deform a wire or the like, means mounted on said body operable to grip and stretch a wire by movement perpendicular to the wire, said movement causing the wire to bend at two points, an anti-friction roller supported on said body to facilitate bending at one of said points, the other point of bending occurring at the point of gripping, and a transverse slot cut in said body to permit free passage of the wire out of said body beyond the point of gripping.

7. In a hand tool of the character described, the combination of a tubular member, means movably mounted within said tubular member arranged to grip a wire positioned across one end of said tubular member and movable inwardly of said tubular

- member to stretch the wire, said tubular member having a slot in one side thereof to prevent bending of said wire on one side of said means.
8. In a hand tool of the character described, the combination of a body having a supporting handle, means mounted on said body operable to deform a wire, means mounted on said body operable to grip and stretch a wire, and a second handle operable by a scissors-like movement relatively to said supporting handle to operate one of said means.
9. In a tool of the character described, the combination of a body providing a supporting handle, swaging and shearing means mounted on said body, a rotatable member in said body for operating said means, gripping and stretching means mounted on said body, a crank handle on said rotatable member for rotating said member, said handle being pivotally connected to said member for scissors-like movement toward and from said supporting handle, and a connection between said crank handle and said gripping and stretching means whereby said gripping and stretching means may be operated by pivotal movement of said crank handle toward said operating handle.
10. A tool for operating on a wire or the like comprising, in combination, a first means for stretching a wire which is fixed at one end, means operable to swage such a wire between the fixed end and said first means while it is maintained in stretched condition by said first means, means for severing the wire, and mechanism operable to actuate successively said stretching means, said swaging means and said severing means.
11. A hand tool for operating on a wire or the like comprising, in combination, a first means for stretching a wire which is fixed at one end, means operable to swage such a wire between the fixed end and said first means while it is maintained in stretched condition by said first means, and means operable to actuate successively said stretching means and said swaging means.
12. A hand tool for operating upon a wire or the like comprising, in combination, a body having a supporting handle, a first means on said body for stretching a wire, a second means on said body for swaging a wire tensioned by said stretching means, and mechanism supported by said body operable to actuate said stretching means and said swaging means, said mechanism having a handle operable by one movement to operate said first means without affecting the other and operable by another movement to operate said second means without affecting the first.
13. A hand tool for operating upon a wire which projects longitudinally through a roll of sheet material, said tool comprising, in combination, a body providing a supporting handle, a head projecting laterally from said body and adapted to be positioned with one side in abutment with a disk at the end of a roll, means mounted on said body operable to grip and stretch a wire projecting through such a disk, means mounted on one side of said head operable to upset such a wire adjacent the disk, and an operating handle for said gripping and stretching means and said upsetting means, said handle being positioned in spaced relation to said head and on the opposite side of said body past the side of the roll upon which the tool is being used whereby to permit operation of said handle.
14. In a hand tool of the character described, the combination of a body providing a supporting handle for the tool, swaging means mounted on said body at one side of said handle, and operating means for said swaging means mounted on said body on the opposite side of said handle.
15. In a tool of the character described, the combination of a body, means on said body for stretching the wire, means mounted on one side of said body for swaging the wire, and means mounted on the same side of said body for severing the wire, and mechanism supported by said body operable to actuate said swaging means and said severing means, said mechanism including cam means mounted on the side of the body opposite to the side on which said swaging and said severing means are mounted.
16. A tool for operating on a wire or the like comprising, in combination, a body having a head extending therefrom, means for stretching a wire, means for swaging such a wire, means for severing the wire, and mechanism operable to actuate said means, said swaging means being located on an outside face of the head, said stretching means being mounted on said body adjacent thereto and said severing means being mounted between said swaging means and said stretching means.
17. A hand tool of the character described comprising, in combination, a body adapted to be supported in abutment with a package or the like, means mounted on said body operable to deform a wire projecting from such a package at a point immediately adjacent the package, stretching means mounted on said body operable to draw the wire past the deforming means prior to the operation of said deforming means, and operating mechanism for said means including a handle mounted on said body in laterally spaced relation to said deforming means.
18. In a hand tool of the character described, the combination of a body adapted to be positioned in abutment with a package having a wire projecting therefrom, and

means mounted on said body operable to stretch the wire and to deform said wire adjacent the package, both of said operations being performed while said body is maintained in one position relatively to said package.

19. A hand tool for operating on a wire or the like comprising, in combination, a body, means mounted on said body for stretching a wire, means for deforming such a wire, said deforming means being mounted on said body adjacent to an outside face thereof so that a wire projecting through an object may be deformed in close proximity to the surface of such an object, and mechanism carried on said body operable to actuate said means.

20. A tool for operating on a wire or the like comprising, in combination, means for gripping and stretching a wire, means for swaging such a wire, means for severing the wire, and mechanism operable to actuate successively said gripping and stretching means, said swaging means and said severing means, said gripping and stretching means holding the wire under tension and in position for operation of said swaging means, and said swaging means coacting with said severing means to hold and cut off the wire.

21. A tool for operating on a wire or the like comprising, in combination, a body with supporting means, means on said body for gripping and stretching a wire which is fixed at one end, means on said body operable to swage such a wire between said fixed end and said gripping means while the wire is maintained in stretched condition by said means, means on said body for severing the wire, and mechanism supported by said body operable to actuate said means in definite predetermined relation to each other.

22. In a hand tool of the character described for operating on a wire or the like, the combination of means for swaging a wire and means for severing such a wire, said swaging means having a stationary jaw and a movable jaw, said severing means having a movable jaw arranged to coact with the movable jaw of said swaging means to sever a wire.

23. In a tool for operating on a wire or the like, the combination of means for stretching the wire, means for swaging the wire, and means for severing the wire, said swaging means having a stationary jaw and a movable jaw, and said severing means comprising a movable jaw coacting with the movable jaw of said swaging means to sever the wire.

24. In a hand tool of the character described, the combination of a tubular member, a rod slidably mounted in said tubular member, means for moving said rod through said member, and gripping jaws mounted

on one end of said rod and automatically operable during movement of said rod to grip a wire, said gripping means being arranged to permit a wire to slide therethrough after a predetermined tension has been applied to said wire.

25. A tool for operating on a wire or the like comprising, in combination, a supporting body, means mounted on said body operable to grasp a wire which projects past one side of and across said body and to move said wire relatively to said side to bring the wire to a desired tension, and means mounted on said body operable to form an abutment on said wire adjacent said side of said body.

26. A hand tool for operating on a wire which extends through a roll of material and through a disk abutting the end of the roll, said tool comprising a body adapted to bear against the disk, a pair of gripping jaws on said body for gripping the wire, and a handle on said body operatively connected to said jaws and movable to press said body against said disk and move said jaws relatively to said disk whereby to cause said jaws to grip a wire and to tension the wire thus gripped.

27. In a tool for operating on a wire or the like, the combination of a cylindrical body, a rod slideable longitudinally in said body, an abutment on one end of said rod to grip the wire, whereby the wire may be stretched by longitudinal movement of the rod, means operable by rotation of said body to deform the wire, a crank handle for rotating said body, said crank handle being pivotally connected to said body for movement in a plane containing the body, and a connection between said crank handle and said rod operable by a movement of said crank handle from a position substantially parallel to said body to a position substantially perpendicular to said body to move the rod to stretch a wire.

28. The method of preparing rolled sheet material for shipment or storage which consists in placing a disk with a wire fastened thereto so that the disk is in abutment with one end of the roll with the wire extending through the central passage of said roll and projecting out of the other end of the roll, placing an apertured end disk against said other end of the roll with the projecting end of said wire extending through the aperture in said disk, placing the wire under a predetermined tension by applying force to said projecting end thereof, and applying pressure to opposite sides of said projecting end of the wire while it is under tension to increase the effective width of said wire and provide an abutment on the outer side of the adjacent disk so that the tension in said wire will maintain said disks in firm abutment with the ends of the roll.

29. The method of preparing rolled sheet material for shipment or storage which consists in positioning a disk with a wire fastened thereto so that the disk abuts one end of the roll and the wire extends through the roll longitudinally thereof and projects out of the other end of the roll, placing an apertured disk in abutment with the other end of the roll with the projecting end of 5 said wire extending through the aperture in the disk, placing the wire under a predetermined tension by applying force to said projecting end thereof to stretch the wire, and applying pressure to opposite sides of the 10 projecting end of the wire immediately adjacent to the disk while the wire is held at said predetermined tension and the disk is held against the end of the roll to increase the effective width of the wire and form 15 an abutment thereon so that the tension in 20 said wire will hold the disk in firm abutment with the roll.

In testimony whereof we have hereunto affixed our signatures.
